PER JOHAN HEDLUND, OF STOCKHOLM, SWEDEN.

STEAM-TURBINE.

SPECIFICATION forming part of Letters Patent No. 767,689, dated August 16, 1904.

Application filed June 13, 1903. Serial No. 161,327. (No model.)

To all whom it may concern:

Be it known that I, PER JOHAN HEDLUND, of Stockholm, Sweden, have invented a new and useful Improvement in Steam-Turbines, of 5 which the following is a specification.

The invention relates to a compound elastic-fluid turbine; and it consists in the construction hereinafter described whereby the absolute velocity of the working fluid before 10 entering each wheel of the compound series is rendered a maximum and the corresponding pressure a minimum, while the outlet velocity is made a minimum and the pressure a maximum, the object being at each stage to 15 store the energy which has not been transformed into work in each successive wheel.

In the accompanying drawings, Figure 1 is a vertical longitudinal section of my improved compound turbine, showing two units and 20 part of another, together with the intermediate fixed guide-channels. Fig. 2 is a horizontal section showing the disposition of the wheel-buckets and guide-blades, other parts being omitted for clearness. Fig. 3 illustrates diagrammatically the conditions of 25 velocity and pressure.

Similar numbers and letters of reference indicate like parts.

1 is the wheel-shaft, 2 the wheel-casing, 30 (broken at 3,) and 4 a chamber into which the working fluid enters at 5. On the shaft 1 are fixed any desired number of wheels, each forming a unit in the compounded series. Thus a wheel is shown at 6, another at 7, and 35 part of a third at 8. Between the successive wheels are interposed fixed partitions 9 and 10, through which partitions the shaft 2 passes.

In each wheel near the circumference is an annular opening 11, the width of which 40 measured radially the wheel increases from inlet 12 to outlet 13. In the fixed partitions are annular openings 14, the width of which similarly measured decrease from inlet 15 to outlet 16. The width of the outlet 13 of each 45 wheel may be equal to the width of the inlet 15 of each partition. The width of the outlet 16 of each partition may be equal to the width of the inlet 12 of the wheel into which it delivers working fluid.

50 In the annular opening 11 of each wheel

are disposed the wheel-buckets, only three of which are here shown at 17 18 19. These buckets are of like curvature and parallel. In the annular opening 14 of each partition are disposed guide-blades (only three here shown) 55 20 21 22. The intervals separating these guide-blades 20 21 22 equal the intervals separating the buckets 17 18 19.

Communicating with the chamber 5 is an annular opening 23, which is contracted from 60 its inlet 24 to its outlet 25. In said opening are disposed parallel guide-blades 26.

The working fluid passing through the opening 23 and between the guide-blades therein acts by impact upon the buckets of wheel 6 65 and then goes to passage 14, wheel 7, and so on through the wheels and intermediate passages, thus causing rotation of the wheels.

As the wheels are of the impact type, the absolute velocity of the fluid before entering 70 each wheel of the series should be a maximum and the corresponding pressure should be a minimum. The absolute outlet velocity should be a minimum, which can be accomplished by making the pressure at this point a maximum, thus storing the energy which has not 75 been transformed into work in the wheel. This is achieved by the construction shown.

The operation is graphically shown in Fig. 3, in which the curves *a* in full lines indicate 80 changes in pressure and the curves *b* in dotted lines changes in velocity. The working fluid moves in the direction of the axis *o x*, and the rise and fall of pressure and velocity are indicated with respect to the axis *o y* at right 85 angles to *o x*. The dotted lines *c d*, *e f*, &c., show the points in wheels and casing where the velocity and pressure relations herein- 90 after noted take place. Following the line *a*, representing pressure, it will be seen that this is at a minimum at the points *A*, which correspond to the contracted passages 25 16, and at a maximum at points *B*, which correspond to the wheel-outlets 13. The line *b*, repre- 95 senting velocity, on the other hand, shows a maximum at *A* and minimum at *B*. Hence at entrance-points *A* there is maximum velocity and minimum pressure and at outlet- 100 points *B* minimum velocity and maximum pressure.

I claim--

1. The combination with an elastic-fluid turbine of the axial-flow type having a passage for working fluid and buckets therein, of means for increasing the velocity and reducing the pressure of the fluid prior to entering said passage and means for reducing the velocity and increasing the pressure within said passage and for reducing the pressure and increasing the velocity of the exhaust.

2. The combination of two elastic-fluid turbines, disposed in series each having a passage gradually expanding from entrance to outlet in the direction of fluid-flow, and buckets in said passages, of means interposed between said wheels for increasing the velocity and reducing the pressure of the exhaust of one wheel prior to its entrance to the other wheel.

3. The combination in an elastic-fluid turbine of the axial-flow type, of a wheel having an annular passage gradually expanding from inlet to outlet in the direction of fluid-flow and buckets therein, a wall on the inlet side of said wheel having an annular passage with its outlet registering with the wheel-inlet, and a wall on the outlet side of said wheel having an annular passage gradually diminishing from inlet to outlet and having its inlet registering with the outlet of said wheel.

In testimony whereof I have signed my name to this specification in the presence of two subscribing witnesses.

PER JOHAN HEDLUND
